JAR CAP WRENCH

Charles Stegmeier, Auburn, Calif.

Application March 22, 1939, Serial No. 263,314

1 Claim. (Cl. 81—3.1)

This invention relates to jar cap wrenches or tools for applying or removing the screw caps of fruit jars and the like, and the primary object of the invention is to provide a tool of this kind in an economical and efficient form of construction.

Another object is to provide a jar cap wrench comprising an elongated handle having a press foot or spur projected from the side of the working end thereof in spaced relation to the extremity of said end portion, the handle end being apertured outwardly of the spur, and an operating strap having one end secured to the extremity of the handle outwardly of the apertured end, the free end of the strap being adapted to embrace the cap of a jar and thence to be passed through the said aperture in the end of the handle and underneath the said spur, whereby by rocking the handle in the direction of the free end of the strap as placed around the jar cap, the press foot or spur is caused to pinch the free end of the strap against the margin of the jar cap, thereby locking the strap against sliding and enabling the tool to unscrew the jar cap from the body of the jar.

Another object is to provide a tool of the kind described, including an elongated handle having an aperture or eye formed through one end thereof, and having a press foot or spur extended laterally from the end of the handle immediately inwardly of the said aperture, and a strap having one end secured to the outer end bight or margin of the aperture and its free end brought around and passed through the said aperture immediately under the said press foot or spur, whereby the strap may be placed around the cap of a jar and drawn taut therearound, and the handle then operated as a lever for unscrewing the cap from the jar, in which operation the said press foot or spur of the handle will ride upon the free end of the strap and press same upon the immediately underlying portion of the same strap and pinch and lock the strap against slideable movement.

With the foregoing objects and advantages in view, attention is directed to the accompanying drawing wherein,

Figure 1 is an elevation of the upper section of a fruit jar having a screw cap mounted thereon, and showing my improved cap wrench operatively applied thereto, as in use, the outer end of the handle of the tool being broken off.

Figure 2 is a top plan view of the assembly shown in Figure 1.

Figure 3 is a detail view, in perspective and

somewhat reduced, of the lever-handle portion of the tool, the strap being omitted.

The invention comprises an elongated handle represented generally at 5, and which may be constructed of tough hard wood, or any other suitable material. An aperture or eye 6 is pierced through the predetermined working end of the handle, the same being preferably rectangular in form and including an outer or marginal bight 7 and spaced marginal side portions 8 which define the said aperture.

A press foot or spur 9 is extended laterally from the apertured end of the handle immediately inward of the said aperture 6, the same being flat, of approximately the same width as the width of the eye 6, and being extended at a slight angle outwardly from the plane of the eye 6, as clearly shown in the drawing.

An operating strap 10 of leather or other suitably flexible material, is cut to a length sufficient to pass around the jar cap 11 one and one-quarter times, approximately, so as to provide at all times a free end of the strap for the accommodation of jar caps of varying sizes, as mounted upon their jars, one of such jars being represented at 12, and being of the conventional screw top form.

The strap 10 is cut to a width approximately corresponding to the width of the eye or aperture 6 of the end of the handle. One end of the strap is anchored to the bight 7 of the eye 6 in any conventional manner as by encircling the bight with the strap and then riveting the end of the strap down to the main strap, as shown at 14. The opposite free end 10a of this strap is then brought around to form a loop 15 adapted to embrace the jar cap 11, and the end is passed slidably through the said eye 6 of the handle 5, immediately under the press foot or spur 9.

In use, the loop 15 of the strap is placed as aforesaid around the jar cap 11 and is drawn taut by pulling upon the free end 10a of the strap, in which operation the end 10a will overlie the main body portion of the strap as represented at 10b. The placement of the strap is in a direction corresponding to the direction in which it is desired to turn the cap. This movement would of course be in a clock-wise direction for installing the cap upon the jar, and in an anti-clockwise direction for removing the cap, under the conventional mode of forming the screw tops of the jars and the threading of the caps. The press foot or spur 9 is extended over the free end 10a of the strap in either case, in which position it will bear down upon this end 55

of the taut strap and will pinch and lock the same against the underlying portion 16b, and this in turn pinching against the flange of the jar top, will effectually lock the strap against slippage. In this operation the handle 5 is of course rocked in the direction of the free end of the strap, and the jar itself being held firmly by one hand, the operator is then enabled to unscrew or screw up the cap relative to the jar by 10 using said handle as a lever.

While I have herein shown and described a certain form of structure for the tool, it is understood I may vary same in minor details, not departing however from the essence of the invention as defined in the appended claim. For instance if desired a ring 17 may be mounted at 15 the free end of the strap for retaining the strap against sliding out through the eye 6.

I claim:

A jar cap wrench comprising a handle having an end portion with a rectangular eye formed therethrough, a press foot or spur extended laterally from the end of the handle at a point immediately back of the eye and lying in the direction of the eye opening, and a strap anchored at one end to the bight of the eye, the opposite free end of the strap being passed slidably through the said eye from the side opposite to the said press 10 foot or spur and being extended underneath said press foot or spur, whereby the strap may be looped around a jar cap and the handle rocked to lock the strap operatively around the cap. 5

CHARLES STEGMEIER.
